ADJUSTABLE FOOT FOR PALLETIZED LOADS
 Raymond Shile, 12 Wolf Road, Croton on Hudson, N.Y.
 Filed Mar. 6, 1961, Ser. No. 93,617
 5 Claims. (Cl. 248—193)

This invention relates generally to the field of material handling, and more particularly to an improved adjustable foot construction for use in conjunction with metal and wood pallets of a type used for supporting relatively heavy loads for convenient handling by means of fork lift trucks and the like.

Devices of this type have found increasing acceptance in recent years, and have materially facilitated the loading and unloading of vehicles, the storage of palletized loads either in horizontal or vertical stacked disposition. To facilitate vertical stacking of the devices, they have normally been provided with vertically disposed angle iron leg elements together with a funnel-shaped foot which permits the camming of the legs of stacked pallets into coaxial alignment. The funnel-shaped construction, while durable and accomplishing its desired end, has had two accompanying disadvantages, one of which is the tendency to damage flooring upon which it is disposed during horizontal shifting, as when moving a loaded pallet to a desired position upon the floor, and the other of which is the difficulty in arranging a plurality of pallets in close horizontal proximity, because of the fact that the feet positioned on the lower extremities of the leg members extend outwardly of the horizontal dimensions of the pallet itself.

It is therefore among the principal objects of the present invention to provide an improved foot construction of the class described in which the above-mentioned disadvantages have been substantially eliminated.

Another object of the invention lies in the provision of an improved palletized load foot construction in which the principal load-supporting surfaces thereof are of a curved nature with a complete elimination of relatively sharp edges, whereby the same may be readily slid across a wood floor or similar damageable surface without substantially marring the same.

A further object of the invention lies in the provision of an improved pivotally mounted cam element or plurality of the same associated with the lower extremity of each leg member of a pallet which may be moved between either of two positions, in a first position of which the camming surfaces thereof are maintained in an inoperative substantially vertical orientation, and in a second position of which they are aligned to engage the upper edges of a leg member disposed therebeneath and upon which the pallet with which the camming device is associated is supported.

A further object of the invention lies in the provision of structure of the class described in which the cost of fabrication may be of a reasonably low order, with consequent wide sale, distribution and use.

A feature of the invention lies in the fact that the inventive structure may be incorporated into existing metallic pallets at very low cost.

Another feature of the invention lies in the substantial durability of the inventive structure as contrasted with prior art constructions.

In the drawing, to which reference will be made in the specification, similar reference characters have been employed to designate corresponding parts throughout the several views.

FIGURE 1 is a fragmentary view in perspective of an embodiment of the invention.

FIGURE 2 is a fragmentary side elevational view thereof, showing a plurality of the inventive devices held in inoperative position.

2

FIGURE 3 is an enlarged fragmentary view in elevation showing the side opposite that seen in the lower portion of FIGURE 2.

FIGURE 4 is an enlarged horizontal view as seen from the plane 4—4 in FIGURE 1.

FIGURE 5 is an enlarged fragmentary view in elevation, showing the side opposite that seen from the left central portion of FIGURE 1.

FIGURE 6 is a fragmentary enlarged vertical sectional view as seen from the plane 6—6 in FIGURE 1.

FIGURE 7 is a view in elevation as seen from the plane 7—7 in FIGURE 4.

In accordance with the invention, the device, generally indicated by reference character 10, is shown in conjunction with a conventional load-supporting platform means, generally indicated by reference character 11, which may be of a type similar to that disclosed in my co-pending application, Serial No. 837,067, filed August 31, 1959, entitled, Collapsible Stacking Material Handling Devices. The means 11 includes a generally horizontally disposed floor 12 and a plurality of vertically extending angle iron legs 13 including first and second flanges 14 and 15, respectively. The lower end portion 16 forms a continuous generally horizontally disposed edge surface. The device 10 is adapted to be secured to the end portion 16, and includes first and second camming elements 17 and 18, respectively, as well as a generally hemispheroidally-shaped supporting element 19.

The first and second camming elements 17 and 18 are generally similar, each including first and second angularly disposed portions 21 and 22, respectively, interconnected by a bend portion 23. The first portion 21 is bounded by side edges 25 and 26, an end edge 27, an upper surface 28 and a lower surface 29. A bore 30 of generally circular configuration extends through the plane of the member 21 between the surfaces 28 and 29. An inner edge 31 interconnects with the bend portion 23.

The second portion 22 is generally triangularly-shaped, to permit movement within the interior of the element 19, and is bounded by first and second outer edges 32 and 33 as well as a third edge 34 which interconnects with the bend portion 23.

The bend portion 23 is preferably formed integrally with the first and second portions 21 and 22, preferably by forging, and includes an outer curved surface 37, an inner curved surface 38, as well as side edges 39 and 40.

The supporting element 19 is also preferably formed as a casting or forging, and includes an inner surface 43, an outer surface 44, upper edges 45 and 46, as well as a curvilinear edge 47. Extending into the upper edges 45 and 46 are first and second elongated slots 48 and 49 corresponding in length to the width of the bend portion 23 as measured between the side edges 39 and 40. The device 10 is assembled to the respective leg member 13 by welding along the upper edges 45 and 46 after first positioning the cam members 21 and 22 within the slots 48 and 49. In this condition, the cam members 21 and 22 are capable of limited pivotal movement from the position shown in FIGURE 6 to that shown in FIGURE 3.

As will be evident from a consideration of FIGURE 1, each of the legs 13 of a platform means 11 is provided with a device 10. When free of interconnection with adjoining devices, the cam members 21 and 22 will normally assume the position shown in FIGURE 6, wherein the corner 51 formed by the interconnection of the edges 32 and 33 will contact the inner surface 43 of the element 19, at which point substantial equilibrium is achieved. In this condition, the means 11 may be shifted about and stacked upon each other, the outer surface 44 of the elements 19 cooperating with the lower surfaces 29 of the first portions 21 to cam the upper free edges of the legs

13 into the coextensive positions shown in FIGURE 1. Where a plurality of means 11 are placed in abutted side-by-side relationship, the free end edges 27 contact each other to pivot the cam elements 17 and 18 to the positions shown in FIGURE 3, wherein the legs 13 may be placed in abutting relation, the camming elements maintaining this position until subsequent movement occurs between the adjacent means 11. Where desired, the bores 30 may be engaged by hoisting means (not shown) in such manner that the camming action of the device is in no way hindered.

It may thus be seen that I have invented novel and highly useful improvements in adjustable feet for palletized loads, in which the functions of prior art devices are retained with a complete elimination of their accompanying disadvantages. Owing to the presence of a curved lower surface on the supporting element which contacts a floor or other supporting surface, the palletized load may be slid over the floor without damage to the same, and, upon the subsequent positioning of a plurality of palletized loads in close proximity, the camming means is shifted to an inoperative position whereby it occupies no substantial space, and whereby the palletized loads may be placed in mutual abutted relation.

I wish it to be understood that I do not consider the invention limited to the precise details of structure shown and set forth in this specification, for obvious modifications will occur to those skilled in the art to which the invention pertains.

I claim:

1. An adjustable foot construction for supporting palletized loads comprising: a generally vertically disposed leg member having first and second mutually angularly disposed flanges, a rounded base element interconnected to the lower extremity of said leg member, there being a transverse through opening in the area of the interconnection of said leg member and said base element, and a camming element positioned for pivotal movement within said opening.

2. An adjustable foot construction for supporting palletized loads comprising: a generally vertically disposed leg member having first and second mutually angularly disposed flanges, a rounded base element interconnected to the lower extremity of said leg member, there being a transverse through opening in the area of the interconnection of said leg member and said base element, and a camming element positioned for pivotal movement within said opening; said camming element including a first member disposed inwardly of said leg member and a second member disposed outwardly of said leg member.

3. An adjustable foot construction for supporting palletized loads comprising: a generally vertically disposed

leg member having first and second mutually angularly disposed flanges, a rounded base element interconnected to the lower extremity of said leg member, there being a transverse through opening in the area of the interconnection of said leg member and said base element, and a camming element positioned for pivotal movement within said opening; said camming element including a first member disposed inwardly of said leg member and a second member disposed outwardly of said leg member, said outer member being movable between two positions, in one of which it lies substantially vertically disposed, and in another of which it lies at an angle with respect to the vertical.

4. An adjustable foot construction for supporting palletized loads comprising: a generally vertically disposed leg member having first and second mutually angularly disposed flanges, a rounded base element interconnected to the lower extremity of said leg member, there being a transverse through opening in the area of the interconnection of said leg member and said base element, and a camming element positioned for pivotal movement within said opening; said camming element including a first member disposed inwardly of said leg member and a second member disposed outwardly of said leg member, said outer member being movable between two positions, in one of which it lies substantially vertically disposed, and in another of which it lies at an angle with respect to the vertical, and means for limiting the pivotal movement of said cam element between said two positions.

5. An adjustable foot construction for supporting palletized loads comprising: a generally vertically disposed leg member having first and second mutually angularly disposed flanges, a rounded base element interconnected to the lower extremity of said leg member, there being a transverse through opening in the area of the interconnection of said leg member and said base element, and a camming element positioned for pivotal movement within said opening; said camming element including a first member disposed inwardly of said leg member and a second member disposed outwardly of said leg member, said outer member being movable between two positions, in one of which it lies substantially vertically disposed, and in another of which it lies at an angle with respect to the vertical, and means for limiting the pivotal movement of said cam element between said two positions; said base element having a curved outer surface extending below said cam element when disposed in a vertical position.
